UNITED STATES PATENT OFFICE.

EDWIN E. BARNEY, OF NEW ROCHELLE, NEW YORK, ASSIGNOR TO REMINGTON TYPE-WRITER COMPANY, OF ILION, NEW YORK, A CORPORATION OF NEW YORK.

TYPEWRITING MACHINE.

Application filed December 1, 1924. Serial No. 753,112.

To all whom it may concern:

Be it known that I, EDWIN E. BARNEY, citizen of the United States, and resident of New Rochelle, in the county of Westchester and State of New York, have invented certain new and useful Improvements in Type-writing Machines, of which the following is a specification.

My invention relates to typewriting machines and more particularly to shielding and protecting means for a portable typewriting machine in which parts are shifted from a compact to an expanded position for use.

The main object of my invention, generally stated, is to provide inexpensive and highly efficient means of the character specified.

To the above and other ends which will hereinafter appear, my invention consists in the features of construction, arrangement of parts, and combinations of devices set forth in the following description and particularly pointed out in the appended claims.

In the accompanying drawings wherein like reference characters indicate corresponding parts in the different views,

Figure 1 is a fragmentary fore-and-aft vertical sectional view with parts omitted, of a Remington portable typewriting machine embodying my invention; the section being taken about centrally through the machine with the carriage shown shifted to the right.

Figure 2 is a detail fragmentary elevation of one of the type bar shields or guards and the companion end type bar; the view illustrating the parts as they appear when seen from the direction of the arrow in Fig. 4 with the shield and type bar expanded in position for use.

Figure 3 is a fragmentary detail vertical sectional view showing the type bar shifting member lowered and parts associated with said member.

Figure 4 is a detail top plan view of a portion of the machine showing the type bar shields and type bars in compact position ready for inclosure within the usual carrying case.

I have shown my invention embodied in the present instance in a Remington portable machine in which the invention may be readily incorporated with but little change

in the existing structure of said machine. It should be understood, however, that the invention is not confined to embodiment in such machine.

In the Remington portable machine, printing key levers 1 are fulcrumed at 2 and are received in an inner frame 3 surrounded by an outer sheet metal frame 4. Each key lever 1 is operatively connected through a link 5, sub-lever 6, link 7, sub-lever 8 and intermeshing gear segments 9 and 10 with the associated type bar 11. The type bars are all pivoted on a pivot wire 12 to strike downwardly from their upright position for use against the top of a platen 13. The platen is mounted on the carriage 14 in the usual manner to travel from side to side of the machine.

Type bars are adapted to be simultaneously turned on their pivots from a compact, recumbent, substantially horizontally disposed position, shown in Fig. 3, to an upright expanded position for use, indicated in Fig. 1. The means employed to control these pivotal movements of the type bars to and from expanded position comprises a finger piece 15 extending to the outside of the machine and carried by a crank arm 16. This crank arm is secured to a rock shaft 17 which extends across the machine and is mounted at its ends in bearing openings in the inner frame 3. Two additional crank arms 18 are fixed to the rock shaft and are pivoted to links 19 which in turn are pivoted, at 19^a, at their upper ends to bracket ears 20 fixed to a plate-like member 21 by which the type bars are elevated and lowered around their pivots. This member 21 may be made of sheet metal and is in the nature of a cover plate and type bar rest carrying a felt pad 22 against which the type bars bear in both expanded and compact positions. The member 21 carries depending substantially vertically disposed arms 23 at opposite sides thereof, said arms working in grooved guide-ways in fixed upright guide members 24. In this manner the member 21 is supported and guided for vertical movement when the rock shaft 17 is turned by the finger piece 15.

In accordance with my present invention, the forward edge 25 of the member 21 is curved and extends beyond the free ends of the type bars and adjacent to a correspondingly rear curved edge 26 of a top plate 27

secured to the machine frame. The forward curved edge 25 of the member 21 is provided with a depending vertically arranged flange or apron 21^a located adjacent to the inner curved edge or wall 26 of the top plate 27. When the member 21 is lowered as shown in Fig. 3, the top thereof is located a considerable distance below the highest part of the top plate 27, but is nevertheless surrounded by the curved edge or wall 26 of the top plate. When the member 21 is elevated, as shown in Fig. 1, the lower end of the apron or flange 21^a is below the upper edge of the top plate and within and adjacent to the curved wall 26 thereof. It will be understood therefore that the apron 21^a at all times substantially closes the space between the member 21 and the top plate 27 and prevents the admission of dust to the underlying actuating connections between the key levers and type bars and other operating parts of the machine. Therefore this member 21 and its flange 21^a, together with the top plate 27 and the frame of the machine, incloses and houses many of the working parts of the machine; housing and guarding them against the admission of dust and hiding them from view, this being true whether the type bars are in the compact position or in the expanded position for use.

In the present instance I form the member 21 with a hollow bead 28 concentric with the front curved edge 25, said bead providing a channel in the bottom of said member 21. From an inspection of Fig. 3, it will be seen that when the type bars are collapsed, the ends of the links 7 and sub-levers 8, (where they are pivotally united) are received in the channel formed by the bead 28 and do not obstruct the down movement of the member 21 to its lowermost position.

This construction not only aids materially in housing working parts of the machine and protecting them, but also presents a neat and finished appearance to the machine whether the latter is conditioned for use or for inclosure within its carrying case.

To further aid in protecting working parts of the machine, and in preventing the hands of the operator from coming in contact therewith in manipulating the machine, I have provided additional guarding or shielding means which will now be described.

Outside of each end type bar of the system, I provide a guard or shield that is movable with the type bars in their pivotal movements to and from expanded position for use. By these means the shields are effective when the type bars are conditioned for use, and when the latter are collapsed or moved to compact position said shields will not add anything to the dimensions of the compacted machine, as will now appear.

In a machine of the character shown, it is necessary for the operator to reach over

the system of type bars, when they are conditioned for use, to effect an adjustment or return movement of the carriage, or to adjust the paper. In the present instance I contemplate providing a finger piece 29 by which the platen may be line spaced and the carriage returned by a single operation, and by a swinging movement of the left-hand of the operator from left to right and slightly forward. For the purpose of my present invention, it is unnecessary to illustrate the means controlled by the line spacing handle. Such means are to form the subject matter of a separate application filed Dec. 22, 1924, Sr. No. 757,545. In adjusting or returning the carriage, or adjusting the paper, one or the other or both hands of the operator might come in conflict with the end type bars of the system. Aside from any possibility of injury to, or bending of, the type bars, the hands of the operator may become soiled and possibly scratched or cut on the sharp corners of the type blocks at the ends of the system. By my present invention, I overcome this difficulty by providing the type bar guards or shields hereinbefore referred to. Each shield is designated as a whole by the reference numeral 30 and preferably consists of a sheet metal member curved in cross section, especially at the outer end portion thereof so as not to present any sharp corners or edges with which the hands of the operator might come in contact. Each shield is pivoted near one end, at 31, to an ear 32 provided on an existing plate 33 secured to the fixed type bar segment 34 by a screw 35. The pivot 31 of each shield is located adjacent to the pivot of the associated end type bar, as will be seen at the right-hand side of Fig. 4. This is in order to enable each shield to swing with its associated end type bar and maintain substantially the same relation thereto in the recumbent and expanded position of each of said bars. Each shield extends lengthwise of, substantially parallel with and outside of the body portion of its associated type bar. It will be seen that the end type bars of the system flare outwardly at their type-carrying ends, and the outer end portion 36 of each shield is flared to correspond to the companion end type bar, and also is curved at 37 to pass over and around the ends of several type bars at the corresponding end of the system.

In order to cause the shields to move in unison with the type bars in their shifting movements to and from expanded position, I operatively connect the shields with the means by which the type bars are thus shifted. In the present instance this connection is effected by providing a pin-and-slot connection between the member 21 and each shield. Thus, a bracket 38 is fixed to the member 21 at each side thereof and carries

a shouldered headed screw or pin 39. The shank of each pin passes freely through a slot 40 in and extending longitudinally of the associated shield 30. Therefore, when 5 the member 21 is lowered, the shields 30 will be carried down around their pivots 31 and moved to a compact position corresponding to the type bars, as shown in Figs. 3 and 4. When the member 21 is elevated, the 10 shields 30 are moved to upright expanded position corresponding to the expanded position of the type bars, to protect the end bars of the system against the hands of the operator colliding therewith and to protect the 15 hands of the operator from being soiled or injured.

In the present instance the arms 20, 23 and 38 are formed integral with a plate 41 riveted at 42 or otherwise secured to the 20 member 21; the rivets 42 also securing the plate 43 for the pad 22 in place.

From the foregoing description it will be seen that I have provided simple and effective means for protecting working parts of 25 the machine which may readily be embodied in a Remington portable machine without material modification of the existing structure.

Various changes may be made without de- 30 parting from the invention as it is defined in the following claims.

What I claim as new and desire to secure by Letters Patent is:—

1. In a typewriting machine, the combination of type bars mounted for movement from a compact position to an expanded position for use, and a guard or shield movable with said type bars from compact to expanded position and operative to protect a 40 hand of the operator from colliding with the type bars.

2. In a typewriting machine, the combination of type bars mounted for movement from a compact position to an expanded position for use, and two guards or shields one 45 located at each end of the system of type bars, said guards being movable with the type bars from compact to expanded position and operative to protect the hands of 50 the operator from colliding with the type bars at both ends of the system.

3. In a typewriting machine, the combination of a system of type bars, shifting means for moving said system of type bars from a 55 compact position to an expanded position for use, and type bar guarding or shielding means connected with and controlled by said shifting means and movable thereby with the system of type bars from compact to expanded position and when in said last named 60 position guarding the hands of the operator against collision with the type bars at the ends of the system.

4. In a typewriting machine, the combination of a system of pivoted type bars, means

for simultaneously shifting all of said type bars around their pivots from a compact position to an expanded position for use, type bar guarding means pivoted to move with the type bars in said movements thereof 70 from compact to expanded position and to guard both ends of the system when the type bars are in condition for use.

5. In a typewriting machine, the combination of a system of pivoted type bars, hand controlled shifting means for simultaneously shifting all of said type bars around their pivots from a recumbent compact position to an upright expanded position for use, a type bar protecting guard or shield pivoted 80 at each end of the system of type bars at or near the pivotal centers of the end type bars, and connections between each of said guards and said shifting means to cause the guards to move in unison with said type bars in 85 their shifting movements from and to compact position.

6. In a typewriting machine, the combination of a system of pivoted type bars, a rest on which said type bars are supported, hand controlled means for shifting said rest to simultaneously shift all of said type bars on their pivots from a compact position to an expanded position for use, pivoted type bar guards or shields, and pin and slot connec- 90 tions between said guards and type rest to cause the guards to shift with the type bars in their movements from compact to expanded position and vice versa.

7. In a typewriting machine, the combination of a system of type bars, means for shifting said system of type bars from a recumbent compact position to an expanded position for use, two type bar guards or shields one arranged at each end of the system of type bars, each guard extending substantially parallel with an end type bar and around and over the free end thereof, and means for operatively connecting said guards with said shifting means to be shifted 105 thereby.

8. In a typewriting machine, the combination of a system of type bars, the end bars of the system having their type carrying ends flaring outwardly, means for shifting said 110 type bars from a compact position to an expanded position for use, two type bar guards or shields one arranged at each end of the system of type bars and extending substantially parallel with said end type bars and 115 flared to correspond thereto and extending around or over the free ends thereof, and connections between said guards and shifting means for causing the guards to shift in unison with the type bars.

9. In a typewriting machine, the combination of a system of pivoted type bars shiftable around their pivots from a recumbent compact position to an upright expanded position, a type bar rest, hand con- 120 125 130

trolled means for shifting said rest to control the shifting movements of the type bars to and from compact position, pivoted type guards or shields one arranged at each end 5 of the system of type bars, each guard extending outside of and substantially parallel with an end type bar and having a longitudinally extending slot therein, and pins carried by said type bar rest and extending 10 into said slots in the guards to cause the guards to partake of the shifting movements of the type bars into and out of compact position.

10. In a typewriting machine, the combination of a carriage, a platen carried thereby, a system of pivoted type bars movable around their pivots from a compact recumbent substantially horizontal collapsed position to an upright expanded position 15 for use, from which latter position the type bars strike downwardly to impact against the top surface of the platen, and two type bar shields arranged at opposite ends of the system of type bars to protect the hands of 20 the operator, each shield being pivoted adjacent to the pivot of an end type bar of the system to move therewith in the movement of the type bars to and from expanded position, means for simultaneously shifting 25 all of said type bars back and forth from expanded to collapsed position, and actuating connections between said shields and said shifting means for causing the shields to partake of the said shifting movements 30 of the type bars.

11. In a typewriting machine, the combination of a system of type bars shiftable from a collapsed to an expanded position for use, means for thus shifting the type 40 bars, a type bar protecting shield arranged at one end of the system of type bars and comprising a sheet metal arm curved in cross section and extending throughout the length of an end type bar, means for simultaneously shifting the type bars to and 45 from expanded position for use, and means controlled thereby for correspondingly shifting said protecting shield.

12. In a typewriting machine, the combination of a system of type bars shiftable from a collapsed to an expanded position for use, including end type bars which are flared outwardly at the type carrying ends thereof, means for shifting said type bars 55 as stated, a type bar protecting shield arranged at one end of the system of type bars and comprising a sheet metal member curved in cross section and extending substantially parallel with the body portion of 60 an end type bar of the system and flared to correspond to the flared type carrying end of said bar and projecting over the free end thereof, means for shifting the type bars as stated, and intermediate connections 65 between said shifting means and shield for

causing the shield to shift with the type bars in said shifting movements of the latter into and out of expanded position for use.

13. In a typewriting machine, the combination of a system of type actions comprising pivoted type bars and keys and actuating connections for said type bars; and means for shifting said type bars around their pivots from compact to an expanded position for use comprising a shiftable type bar supporting plate that overlies said actuating connections and extend forward at least as far as the free ends of the type bars; and a top plate of the machine which terminates at its rear edge just forward of the front edge of said shiftable supporting plate.

14. In a typewriting machine, the combination of a system of type actions comprising pivoted type bars and keys and actuating connections for said type bars; and means for shifting said type bars around their pivots from compact to an expanded position for use comprising a shiftable type bar supporting plate that overlies said actuating connections and extends forward at least as far as the free ends of the type bars, a top plate of the machine which terminates at its rear edge forward of the front edges of said shiftable supporting plate and adjacent thereto, and a substantially vertically disposed flange that closes the space between said shiftable plate and top plate when the shiftable plate is shifted to expand the type bars.

15. In a typewriting machine, the combination of the type bars, and means for shifting said type bars from a compact to an expanded position including a shiftable plate that covers working parts of the machine, said plate having a depending flange extending substantially to and below parts of the frame of the machine to form therewith a protecting housing for working parts of the machine when the type bars are expanded as well as when they are collapsed.

16. In a typewriting machine, the combination of a series of type bars shiftable from a compact recumbent substantially horizontally disposed position to an upstanding expanded position for use, a top plate of the machine which terminates at its rear edge substantially at the free ends of the type bars when the latter are in recumbent position, and means for shifting the type bars as stated comprising a shiftable plate extending at its forward edge substantially to the rear edge of said top plate and provided with a depending flange or apron which closes the space between the top plate and said shiftable plate when the latter is shifted to expand the type bars.

17. In a typewriting machine, the combination of a series of type bars shiftable from a compact recumbent position to an ex-

panded position for use, a top plate of the machine having its rear edge formed in a curve conforming substantially to the free ends of the type bars when the latter are 5 in recumbent position, said rear edge of the top plate terminating near the free ends of the type bars when the latter are in recumbent position, and means for shifting the type bars as stated comprising a shift- 10 able plate extending at its forward edge substantially to the rear edge of said top plate and curved to conform thereto and provided with a depending flange or apron which closes the space between the top plate 15 and said shiftable plate when the latter is shifted to expand the type bars.

18. In a typewriting machine, the combination of a system of pivoted type bars shiftable around their pivots from a recumbent compact position to an upright expanded position for use, key levers, intermediate actuating connections between said key levers and type bars, a top plate of the machine having a rear edge curved to 20 form substantially to the curvature of the free ends of the system of type bars when the latter are in recumbent position, said 25

edge of the top plate terminating near the free ends of the type bars when they are in the recumbent position, and means for shifting the type bars as stated comprising a substantially horizontally disposed shiftable plate beneath the type bars and curved at its forward edges to conform substantially to said curved edge of the top plate 30 and extending substantially thereto, said shiftable plate having a depending flange or apron at the forward curved edge thereof which closes the space between said top plate and shiftable plate when the latter is shifted 35 to expand the type bars and which with the frame, top plate and shiftable plate houses and protects said intermediate actuating connections and other working parts of the machine. 40

Signed at the borough of Manhattan, city of New York, in the county of New York and State of New York this 28th day of November, A. D. 1924. 45
